(57) **CLAIM**

The ornamental design for a poultry holder for roasting pans,
as shown and described.

DESCRIPTION

FIG. 1 is a perspective view of a poultry holder for roasting
pans showing my new design.

FIG. 2 is a front view.

FIG. 3 is a top view.

FIG. 4 is a left hand side view, the right hand side view being
a mirror image thereof.

FIG. 5 is a rear view.

FIG. 6 is a bottom view.

FIG. 7 is a perspective view of a second embodiment of the
invention.

FIG. 8 is a front view thereof.

FIG. 9 is a top view.

FIG. 10 is a left hand side view, the right hand side view
being a mirror image thereof.

FIG. 11 is a rear view.

FIG. 12 is a bottom view.

FIG. 13 is perspective view of a third embodiment of the
present invention.

FIG. 14 is a front view.

FIG. 15 is a top view.

FIG. 16 is a left hand side view, the right hand side view
being a mirror image thereof.

FIG. 17 is a rear view.

FIG. 18 is a bottom view.

FIG. 19 is a perspective view of a fourth embodiment of the
present invention.

FIG. 20 is a front view.

FIG. 21 is a top view.

FIG. 22 is a left hand side view, the right hand side view
being a mirror image thereof.

FIG. 23 is a rear view.

FIG. 24 is a bottom view.

FIG. 25 is a perspective view of a fifth embodiment of the
present invention.

FIG. 26 is a front view.

FIG. 27 is a top view.

FIG. 28 is a left hand side view, the right hand side view
being a mirror image thereof.

FIG. 29 is a rear view; and,

FIG. 30 is a bottom view.

The broken lines shown in the drawings are for illustrative
purposes only and form no part of the claimed design.
